[57] **CLAIM**

The ornamental design for a thin planar flashlight, as shown and described.

DESCRIPTION

FIG. 1 is a front perspective view of a thin planar flashlight showing my new design, a user's hand and a light beam being shown in broken lines for illustrative purposes only, forming no part of the claimed design;
FIG. 2 is a top plan view thereof;
FIG. 3 is a front elevational view thereof;
FIG. 4 is a right side elevational view thereof;
FIG. 5 is a rear elevational view thereof; and,
FIG. 6 is a bottom plan view thereof.
